PERFORATED-PANEL BRACKET
Hugh E. Kerr, Shreve, Ohio
Filed Sept. 25, 1962, Ser. No. 225,988
2 Claims. (Cl. 248—225)

This invention relates to the combination of a bracket with a perforated panel, useful for various purposes. For example, the bracket can be designed for the attachment of one or more objects thereto and it can be used to clamp one or more items to the perforated panel.

The bracket is fastened to the perforated panel by one or more pegs each of which has a rear portion behind the panel, a head or front portion in front of the panel, and an offsetting portion joining the two located in a hole in the panel.

The bracket includes a flat base portion, preferably of sheet metal, which may be placed flat against the face of the perforated panel or it can be used for clamping the thin portion of an object to the panel by locating such thin portion between the bracket and the panel. The bracket is held to the panel by one or more pegs. It may include a projecting portion with a suitable opening through it for tying or otherwise attaching objects to it. An object clamped to the perforated panel may be equipped in any desired manner for display in a salesroom or for any other purpose.

The invention is further described in connection with the accompanying drawings, in which:

FIGURE 1 is a front view of a perforated panel with a bracket fastened to its front face, showing the peg after attachment of the bracket to the panel in full lines, and also in a different position before attachment, in dotted lines;

FIGURE 2 is a section on the line 2—2 of FIGURE 1, showing the left side of the bracket;

FIGURE 3 is a section on the line 3—3 of FIGURE 1, showing the other side of the bracket;

FIGURE 4 is an end view of the bracket on the line 4—4 of FIGURE 2;

FIGURE 5 is a front view of a modified perforated panel with an object positioned on the front face of the perforated panel as it would be held by a bracket, the bracket being omitted to show the manner of attachment of the object to the panel;

FIGURE 6 is a section of the perforated panel on the line 6—6 of FIGURE 5 showing one side of the object on the panel, with the addition of the bracket;

FIGURE 7 is a similar view but on the line 7—7 of FIGURE 5, showing the other side of the object;

FIGURE 8 is a section through the perforated panel on the line 8—8 of FIGURE 5 showing the bottom end of the object;

FIGURE 9 is a section on the line 9—9 of FIGURE 5;

FIGURE 10 is a front elevation of a further modification with a longer bracket held to the perforated panel by two pegs;

FIGURE 11 is a bottom plan view on the line 11—11 of FIGURE 10; and

FIGURE 12 is an end elevation of the same.

The perforated panel 1 is of any usual construction. The openings 2 may be arranged in an orderly fashion, or in any other suitable manner.

The peg 3 is of any usual construction and includes the rear portion 4, the front portion or head 5 which is parallel to the rear portion, and the offsetting portion 6 which connects the front and rear portions. The head may be provided with a hook 7 but for the purposes described the peg need not include a hook. A hook may be convenient for a variety of purposes.

The bracket 10 is preferably made of sheet metal, but

2

may be of glass, plastic, porcelain or other suitable material. It includes the flat base portion 11, and a projection 12 bent perpendicular thereto. The lower end 13 of the projection 12 is bent at right angles to the projection and also at right angles to the base portion 11. The end 13 approaches the base 11 preferably at a point 14 to form the notched opening 15 with the head 5 of the peg releasably engageable in the notch by sliding movement of the head over the face of the base portion 11. Thus, to attach the bracket to a perforated panel, the bracket is placed with the base portion 11 against the face of the panel and with the opening 16 in the base portion coinciding with one of the openings 2 in the panel. The rear portion 4 of the peg is inserted through the openings in the base portion and the panel. Then the head of the peg is pressed flat against the bracket and rotated about the offsetting portion 6 by sliding the head 5 over the face of the base portion into engagement with the notch in the opening 15. In this way the base portion 11 of the bracket is held fast against the face of the panel.

The bracket can be used for any purpose. The opening 18 is provided so that an object can be tied to the bracket for display or any other purpose. Such an opening might be provided in the end 13. The bracket is firmly engaged against the perforated panel and will withstand any considerable pull against any tie made through the opening 18. It will hold a considerable weight. Also, as explained below, the bracket can be used for attachment of another object to the panel. Thus, the combination of such a bracket with the panel widens the usefulness of a panel very materially.

FIGURES 5 to 8 illustrate how an object 20 can be clamped to the perforated panel by a bracket. The bracket may be the bracket 10, although a modified form 10' is shown in the drawings. In this modified form the notch 15' for releasable engagement of the head of the peg is at the base of a triangular projection 13' bent forward at an angle from the base of the bracket.

The bracket is attached horizontally to the panel instead of being vertical, but is not shown in FIGURE 5 in order to show a complete front view of the object 20. There is only one peg holding the bracket to the panel, but it holds it firmly. The foundation of the object 20 is formed of sheet metal and includes a base 21, an attaching portion 22 across its bottom, and sides 23 and 24 which are bent up perpendicularly to the base 21. The attaching portion 22 is clamped between the bracket 10' and the panel. In order to hold the object 20 in position there is an opening 26 in the attaching portion which coincides with the opening 16 in the base portion of the bracket and the opening in the panel. The peg is passed through these various openings and the head is engaged in the notch 15' of the bracket, as previously described.

To steady the object, tabs 28 (FIGURES 6, 7 and 9) 55 cut from the attaching portion 22 and bent down between edges 29 (FIGURE 5) of the attaching portion, are engaged in two of the regular openings 2 in the perforated panel. By passing the peg through an opening in the attaching portion its vertical position is maintained and the tabs 28 prevent the object 20 from swiveling about the peg.

The construction of the object 20 is immaterial. It is shown as comprising a yoke 30 with the ends 31 bent in and engaged in openings in the projections 23 and 24. An arm 32 with a horizontal portion 33 surrounded by the coil spring 34 has a hook 35 at the end which the spring 34 tends to maintain engaged over the yoke, although the hook can be disengaged by downward pressure on the arm 32. When disengaged from the yoke the spring draws the hook 35 against the stop lug 36, and the projection 24 is bent out at 38 to hold the arm 32 in the raised position.

The object attached to the perforated panel can be of any construction. It can be used for any purpose. It is firmly clamped to the panel by the bracket 10'. There is enough spring in the peg that holds the object clamped to the panel so that the same peg can be used whether or not the bracket is used for the attachment of an object to the panel.

The bracket 40 of FIGURES 10-12 is held in place by two pegs 41. Any number of pegs may be employed. By the use of two or more pegs the bracket is held rigidly on the panel. It can not turn as it might if a single peg were used.

The bracket 40 is made of any suitable material. It is preferably made in one piece but may be assembled from various parts. It includes the base 43, the upright 44 and the ends 45. The ends are similar to the end 13 of the bracket shown in FIGURES 1-4, with a notched opening 46 between each end and the base so that the head of each peg can be releasably engaged in its respective notch. When this is done the bracket is held rigidly on the board. The bracket may be horizontal or vertical or located at any angle. If two such brackets are fastened vertically side by side, articles can be laid with their ends in a notch 48 of each for display.

An article can be tied to a single bracket rigidly fastened to a perforated panel, and tension can be applied to it at any angle. For instance, one end of the tape 50 can be tied in one of the holes 51, and the tape can be tied around a tool or the like for display or the tape can be put to any other desired use. The peg 52 tied to the other end of the tape can be engaged in any hole in the panel. The spring 53 is fastened to the tape at locations separated farther than the distance between the two ends of the unstretched spring, the purpose being to keep the tape taut wherever the peg 52 is engaged, provided only that the spring is under some tension.

The invention is covered in the claims which follow.

What I claim is:

1. The combination of a perforated panel with holes therein, a peg and a perforated-panel bracket; which peg

comprises a rear portion behind the panel, a head substantially parallel to said rear portion and in front of the panel, and an offsetting portion located in one of the holes in the panel, which bracket comprises a flat base portion which is generally parallel to the front of the panel, an opening in said base portion in which the offsetting portion of the peg is located with the peg rotatable about the offsetting portion while in the opening with the head slidably positioned against the front of said flat base portion, and means on the front of the bracket adjacent said flat base portion with which the head of the peg is releasably engaged; with an object having a thin base clamped between the panel and the bracket.

2. The combination of a perforated panel with holes therein, two pegs and a perforated-panel bracket; which pegs each comprise a rear portion behind the panel, a head substantially parallel to said rear portion and in front of the panel, and an offsetting portion located in one of the holes in the panel; which bracket comprises a flat base portion which is generally parallel to the front of the panel, two openings in said base portion in each of which is the offsetting portion of a different peg with the pegs rotatable about the offsetting portion while in the respective openings with the head slidably positioned against the front of said flat base portion, and means on the front of the bracket adjacent said flat base portion with which the heads of the pegs are releasably engaged.
